UNITED STATES PATENT OFFICE.

WILLIAM L. KEENE, OF WATERVILLE, MAINE.

DRAFT REGULATOR.

Application filed September 2, 1921. Serial No. 497,998.

To all whom it may concern:

Be it known that I, WILLIAM L. KEENE, a citizen of the United States, residing at Waterville, in the county of Kennebec and 5 State of Maine, have invented certain new and useful Improvements in Draft Regulators, of which the following is a specification.

My said invention relates to an improved 10 heat regulator designed particularly for use in regulating furnaces for dwelling houses and the like but applicable to various heating devices and in various situations.

In its preferred form my invention constitutes an improvement over that described 15 in my application No. 442,178 filed January 25, 1921. It is an object of my invention to prevent stray electrical circuits in the mechanism, the electrical connections being entirely insulated from the frame-work of the 20 device.

Another improvement relates to the construction by which operation of the draft and damper of a furnace or similar controlling elements in other heating instrumentalities are regulated, e. g., according to 25 the pressure in the steam boiler.

Referring to the accompanying drawings which are made a part hereof and on which 30 similar reference characters indicate similar parts,

Figure 1 shows a side elevation of my improved device,

Figure 2 a plan thereof,

Figure 3 a diagrammatical view illustrating the mechanism with which it is used and the relative location of the related devices,

Figure 4, a fragment partly in section 40 showing details of the electric circuit, and

Figure 5, a detail of a sleeve and cams carried thereby.

In the drawings reference character 11 indicates a pressure operated device, here 45 shown as being of the diaphragm type, connected by a pipe 10' to a steam boiler or like instrumentality. A plunger 12 on the diaphragm is adapted to actuate a lever 13 normally depressed by a weight 14. A rod 50 15 extends vertically above the lever 13 and carries an adjustable collar 16 which may be moved into position to hold the rod and connected lever in elevated position or which may be held up by any convenient means, 55 such for example as that shown in my prior application.

On the floor above the pressure device 11 or on a support arranged convenient thereto is a fixed frame 17 which supports a clock-work mechanism. The frame 17 comprises side members which support various elements of the clockwork at different elevations above the floor. These elements include a main shaft 18 having oppositely directed arms 19 and 20 at opposite ends thereof, the arms being shown in dotted lines in Figure 1. Arm 19 is connected by a chain 21 to a rock arm 22 on a damper 23 in the pipe 24 leading from furnace 25. Arm 20 is connected by a chain 26 to the furnace door 27. Counter-weights connected to the arm 22 and to the chain 26 keep them both in open position. Shaft 18 also carries a gear 28 driven by gear 29 mounted on shaft 30. Shaft 30 has fixed thereto a sprocket 31 over which passes a sprocket chain 32. A weight 33 attached to the chain tends to drive the shaft in a clockwise direction. A ratchet 34 also fixed to shaft 30 cooperates with a pawl 35 on gear 29 to drive the gear. A pawl 36 on the frame is normally held out of engagement with a notched disk 37 on shaft 18 by a lever 38, the upward movement of the pawl being limited by a bent wire 39 extending over the pawl. A pin 32' near the end of the chain lifts the lever 38 and lowers the pawl, which engages the notch in disk 37 and stops rotation of shaft 18, to prevent the chain running off the sprocket, and act as a safety device to stop the machine from working with the dampers closed.

Shaft 18 has fixed thereto a gear 40 which drives a pinion 41 on a shaft 42 which also has fixed thereto a gear 43 driving a pinion 44 on a shaft 45. Shaft 45 carries a gear 46 which drives a pinion 47 on a shaft 48. The latter shaft carries a rotary fan brake 49 of ordinary type between the frame members and has wires coiled about one end, the extremities of the wires projecting to form arms 50.

Shaft 18 carries also a series of notched disks 51, 52 and 53 which are adapted to control the ordinary rotations thereof, the first two being integral with a sleeve held on the shaft by a set-screw. A pair of locking pawls 54 and 55 have downward projections resting on the peripheries of the disks 51 and 52 respectively. The disks have each a notch, the notch on one being 180° distant from the other. When either of the

pawls is lowered by registration of its projection with the notch, the forward hooked end of the pawl will engage one of the wire arms 50 and hold the shaft 48 against rotation.

The rod 15 carries a series of adjustable collars 56, 57, 58 and 59 the two last named coacting with a projecting pin 60 on the fixed frame to limit up and down movement of the 10 rod, rod 15 also passing through a guideway in said pin. Collar 56 has a projecting pin 61 engaging a lever 62 pivoted on a bracket 63 projecting from the frame 17, the lever having a bent-up portion engaging locking- 15 pawl 55. Collar 57 has a pin (not shown) projecting directly beneath the locking pawl 54. It will be seen that upward movement of rod 15 will cause the pawl 54 to be raised and will lower the projection of lever 62 to 20 permit depression of pawl 55, whereby its forward end may engage and hold the corresponding arm 50.

The locking-pawls 54 and 55 act alternately to lock the shaft 48 against rotation. 25 A rod 63 is adapted at one end to engage a notch in disk 53. The rod has a sleeve 64 intermediate its length fixed to one section thereof and adjustably connected to the other by a set screw. An armature 65 30 pivotally mounted on a fixed frame is adapted to retract rod 63 and the armature carries a lug or hook to engage the farther arm 50 and so arrest the movements of the entire regulator. A pair of electro-magnets 35 66 when energized retract the armature and the rod connected thereto, the electro-magnets being mounted on an independent support.

The armature has a downward projection 40 with a mass of insulating material 67 attached thereto preferably in the form of a sleeve. A slide 68 controlled by a rocking arm 69 with a handle 70 is provided with a vertical fin 71 by means of which the 45 rod 63 may also be held in retracted position.

The connections hitherto described serve 50 for controlling the operation of the device according to the temperature of the heating medium such as steam or hot water. The invention also comprises an electric circuit for energizing magnets 66. This circuit includes terminals 72 and 73 adapted to be connected in any convenient way to a source 55 of direct current. From terminal 72 a wire 73 passes to an insulated binding-post 74 on the fixed frame, this binding-post being in the form of a bolt having an enlarged head 75 provided with a guide for the rod 63 and preferably enclosing a spring bearing against a shoulder or rod 63 for moving it to the left into engagement with the periphery of disk 53. On one side of the head is mounted a contact member 76 in the 60 form of a leaf-spring which contacts the

periphery of disk 53. This disk is insulated from the shaft and has a projection 77 adapted to contact at intervals with a second leaf-spring contact 78 on an insulated post 79 mounted on frame 17. A wire 80 is fixed at one end to the post 79 and at the other end to the upper electro-magnet. This in turn is electrically connected to the lower electro-magnet and thence by a conductor 81 to terminal 73.

In the operation of the device the chain 32 is pulled down at the left to elevate the weight which drives the train of clockwork. Figure 1 shows the mechanism in the position assumed when the damper and draft are both open. The parts will remain in such position until the temperature of the medium controlling the pressure device 11 (in this case steam under pressure) rises sufficiently to lift the lever 13 and rod 15. When this occurs detent 54 is elevated, releasing the outer wire arm 50. The rotation of shaft 48 now being unopposed weight 33 will cause the clockwork to move until detent 55 engages the notch in disk 52 and its end engages the other wire arm 50 when the rotation of shaft 48 will again be interrupted. The draft and damper are now closed and rod 15 will remain in its upper position so long as the steam pressure continues, the rod holding up locking pawl 54 and leaving pawl 55 in lowered position. When the pressure falls detent 55 will release its arm 50 and shaft 48 will make a few revolutions until rod 63 falls into the notch on disk 53 whereupon armature 65 engages the same arm 50 and the rotation of shaft 18 is stopped. The device is now under control of thermostat 82 which is in circuit with the electro-magnets 66. When the temperature of the room falls to a predetermined level the thermostat will close the circuit and energize the electro-magnets thus removing the armature with its lug out of the path of arm 50 and permitting the weight to rotate shaft 18 until the notch on disk 51 again lowers the detent 54, when the parts are in their original position. The thermostatic control may be omitted if desired, the particular arrangement here shown being intended to prevent overheating of rooms and waste of fuel since mere fall of steam pressure will not open the drafts, the electric circuit preventing such action until the temperature of the rooms to be heated falls sufficiently to close the circuit at the thermostat.

It will be obvious to those skilled in the art that my heat regulator and the various parts thereof may be modified in various particulars without departing from the spirit of the invention or the scope of the appended claims. Therefore I do not limit myself to the specific embodiment of the invention shown in the drawings and de-

70

scribed in the specification but only as indicated in said claims.

Having thus fully described my said invention, what I claim as new and desire to secure by Letters Patent, is:

1. In a heat regulator, a shaft, means connected thereto for operating a draft controlling device of a furnace, clockwork mechanism for driving the shaft, and other mechanism to control said clockwork comprising devices responsive to changes of pressure in the heating medium, substantially as set forth.

2. In a heat regulator, a shaft, means connected thereto for operating a draft controlling device of a furnace, means for driving the shaft, and mechanism to control said driving means comprising clockwork connected to the shaft, a second shaft driven by such clockwork, arms projecting from said shaft, detents to engage the arms and lock the clockwork against movement, temperature controlled means for releasing some of the detents and pressure controlled means for releasing the remainder of the detents, substantially as set forth.

3. In a heat regulator a frame, a shaft, means connected thereto for operating a draft controlling device of a furnace, means for driving the shaft, and mechanism to control said driving means comprising clockwork connected to the shaft, pawls pivoted to the frame and adapted to engage an element of the clockwork to lock the same against movement, temperature controlled means to release said pawls alternately, and disks on said shaft to hold said pawls in released position, substantially as set forth.

4. In a heat regulator a frame, a shaft, means connected thereto for operating a draft controlling device of a furnace, means for driving the shaft, and mechanism to control said driving means comprising clockwork connected to the shaft, pawls pivoted to the frame and adapted to engage an element of the clockwork to lock the same against movement, means connected to the furnace to operate the pawls at times and temperature controlled means for operating said pawls at other times, substantially as set forth.

5. In a heat regulator a frame, a shaft, devices connected thereto for opening and closing the draft controlling means of a furnace, means for driving the shaft, and mechanism to control said driving means comprising clockwork connected to the shaft, pawls pivoted to the frame and adapted to engage an element of the clockwork to lock the same against movement, a pressure device connected to the furnace, means operated by the pressure device for releasing said pawls, and means on the shaft for holding said pawls out of locking position

alternately during a half-revolution of the shaft, substantially as set forth.

6. In a heat regulator, a shaft, means connected thereto for operating a draft controlling device of a furnace, means for driving the shaft, and mechanism to control said driving means comprising locking pawls to engage a moving part of the mechanism and lock the whole against movement, a pressure device connected to the furnace, a reciprocating rod controlled by the pressure device, and means on the rod for alternately releasing said locking pawls, substantially as set forth.

7. In a heat regulator, a shaft, devices connected thereto for opening and closing the draft controlling means of a furnace, means for driving the shaft, and mechanism to control said driving means comprising locking pawls to engage a part of the moving mechanism and lock the whole against movement, means connected to the furnace, a reciprocating rod controlled by the last said means, a lug on the rod adapted to disengage one of the pawls on movement in one direction, a lever engaging the other pawl, and a lug on the rod engaging the lever to disengage said other pawl on movement of the rod in the opposite direction, substantially as set forth.

8. In a draft regulator a frame, a shaft, devices connected thereto for opening and closing the draft controlling means of a furnace, means for driving the shaft, and mechanism to control said driving means comprising a disk on the shaft, insulated therefrom and having a notch, a detent adapted to engage the notch and hold the shaft from rotation, an armature pivoted to the frame and attached to said detent, an electro-magnet for said armature, an energizing circuit for said electro-magnet including a member constantly in contact with said disk and a member positioned to engage a lug on the disk, and a thermostat in a room to be heated said thermostat adapted to close said circuit, substantially as set forth.

9. In a draft regulator, a shaft, means connected thereto for operating a draft controlling device of a furnace, means for driving the shaft, and mechanism to control said driving means comprising means for locking said shaft against movement, an electric circuit to release said locking means, temperature controlled means for closing the circuit at one point to withdraw said locking means at times and other means attached to the furnace for mechanically operating the mechanism to control the said driving means for withdrawing the locking means at other times, substantially as set forth.

10. In a draft regulator, a shaft, means

connected thereto for operating a draft controlling device of a furnace, means for driving the shaft, and mechanism to control said driving means comprising a disk on the shaft insulated therefrom, a lug on the disk, a detent to lock the shaft against rotation, and an electric circuit controlling said detent including a conductor in engagement with the disk and a conductor adapted to engage said lug, substantially as set forth.

11. In a heat regulator, a shaft, means connected thereto for opening and closing a draft controlling device of a furnace, means for driving the shaft, and mechanism to control said driving means comprising a disk on the shaft insulated therefrom, a lug on the disk, a resilient contact member engaging the periphery of the disk, and a resilient contact member adapted to engage said lug, substantially as set forth.

12. In a heat regulator a frame, a shaft, means connected thereto for opening and closing a draft controlling device of a furnace, means for driving the shaft, and mechanism to control said driving means comprising a notched disk on the shaft insulated therefrom, a lug on the disk, a resilient contact member engaging the periphery of the disk and cooperating with the notch to lock the mechanism, a resilient contact member adapted to engage said lug to establish an electrical circuit and insulated binding posts on the frame for said resilient contact members, substantially as set forth.

13. In a heat regulator a frame, a shaft, means connected thereto for opening and closing a draft controlling device of a furnace, means for driving the shaft, and mechanism to control said driving means comprising a disk on the shaft, said disk having a notch, a rod adapted at its end to engage said notch, an electro-magnet adjacent thereto, an armature movably mounted on the frame of the regulator and connected to the rod, a shaft driven from the first said shaft, an arm on the shaft, and a lug on the armature forming a stop for said arm, substantially as set forth.

14. In a heat regulator, a shaft, means connected thereto for opening and closing a draft controlling device of a furnace, means for driving the shaft, and mechanism to control said driving means comprising a plurality of disks on the shaft, a plurality of pawls having lugs resting on some of said disks and adapted to engage notches therein, a shaft driven from the first said shaft, arms on the second shaft adapted to be en-

gaged and held against rotation by said pawls, another pawl adapted to engage one of said arms, means controlled directly from the heating medium for disengaging said first-named pawls and means controlled from a room to be heated for disengaging the last named pawl, substantially as set forth.

15. In a heat regulator, a shaft, means connected thereto for operating a draft controlling device of a furnace, means for driving the shaft, and mechanism to control said driving means comprising a pair of pawls for alternately locking the draft regulating devices in open and in closed position, means operated directly by the heating medium for disengaging said pawls alternately, an additional pawl for locking said mechanism, and means controlled by a thermostat in a room to be heated for releasing said additional pawl, substantially as set forth.

16. In a heat regulator, a shaft, means connected thereto for operating a draft controlling device of a furnace, means for driving the shaft, and mechanism to control said driving means comprising means to lock said draft regulating devices in open position, means to lock them in closed position, means controlled directly from the heating medium for unlocking said locking means, and auxiliary means to prevent opening of the draft controlling devices until a predetermined temperature is reached in the space to be heated, substantially as set forth.

17. In a heat regulator, a shaft, means connected thereto for operating a draft controlling device of a furnace, clockwork mechanism for driving the shaft, and other mechanism to control said clockwork comprising means mechanically connecting the furnace and the said mechanism said means being controlled by the heating medium, substantially as set forth.

18. In a heat regulator, a shaft, means connected thereto for operating a draft controlling device of a furnace, clockwork for driving the shaft, and mechanism to control said clockwork comprising pressure controlled means attached to the furnace and mechanically connected to the said mechanism, substantially as set forth.

In witness whereof, I have hereunto set my hand and seal at Waterville, Maine, this twenty-ninth day of July, A. D. nineteen hundred and twenty-one.

WILLIAM L. KEENE. [L. s.]
